W. A. McDougall,
MEANS FOR DETECTING TILT IN AEROPLANES.
APPLICATION FILED DEC. 6, 1918.

1,412,362.

Patented Apr. 11, 1922.

William Alexander McDougall

UNITED STATES PATENT OFFICE.

WILLIAM ALEXANDER McDougall, OF FOREST HILL, ENGLAND.

MEANS FOR DETECTING TILT IN AEROPLANES.

1,412,362.

Specification of Letters Patent. Patented Apr. 11, 1922.

Application filed December 6, 1918. Serial No. 265,625.

To all whom it may concern:
Be it known that I, WILLIAM ALEXANDER McDougall, of Forest Hill, in the county of London, England, a subject of the King of Great Britain and Ireland, have invented certain new and useful Improvements in Means for Detecting Tilt in Aeroplanes, of which the following is a specification.

This invention relates to aeroplanes, hydro-aeroplanes and other like aerial craft and refers to means for detecting when the flying machine tilts beyond a certain predetermined angle, and for giving warning to the pilot, so that he may be rendered conscious of the tilt, and may make the necessary corrections for restoring the machine to a horizontal position, where so desired.

The essential principle of the invention consists in providing a pendulum like device pivoted to some suitable part of the flying machine, the said device carrying an electric contact, which is adapted when the machine tilts beyond a certain angle to come against another contact, thus completing an electrical circuit through a lamp or other electrical signalling device by means of which the attention of the pilot is attracted, and by which he is warned of the tilt of the machine.

In order that my invention may be more clearly understood, I will now proceed to describe the same with reference to the accompanying drawing, which shows by way of example, in a diagrammatic section, one method of applying the invention to an aeroplane.

Fig. 1 shows the position of the device with the aeroplane in a horizontal position, whilst Fig. 2 shows the position of the device and its operation with the aeroplane in a tilted position.

The same letters of reference denote the same parts in both the views.

a is a bar of wood or other suitable material, suspended between plates *b*, by means of a pivot *b*¹, so that it is free to swing as a pendulum. The plates *b* carrying the pivot are in this case mounted on one of the upper planes of the machine and in practice I prefer to provide two of the apparatus one mounted on each side wing of the aeroplane and to cut a slot in the wing *f*, through which the top of the device passes but if it is not desired to interfere with the construc-

tion of the wing, *f* may represent any suitable transverse horizontal member.

To the lower end of the bar *a* is attached a heavy bob or weight *c*.

e, *e* are vertical struts connected at their lower ends to a horizontal member *g*, such as a lower wing or plane in the case of a biplane and at their upper ends to the wing, plane or its equivalent *f*.

Attached at *i* to the vertical members *e*, is a frame or its equivalent provided with a slot *m* through which the bar *a* passes. This slot is so arranged that it allows the pendulum to swing freely from side to side as the machine tilts around an axis vertical to the plane of the paper, but so that it does not respond when the machine tilts around an axis at right angles to that first mentioned and substantially horizontal, that is when the machine is simply ascending and descending.

In a suitable position on the vertical bar, which position is determined according to the angle at which it is desired that the warning hereinafter mentioned shall be given is provided an electric contact stud or plate *d*, which may be provided with an insulating and buffering means. *d*¹ is a conducting wire leading from the contact, passing up to the pivot *b*¹ and from this wire passes a further conducting wire *l*¹ to an electric lamp *l*. *h* is another contact, which may take the form of an adjustable plate and is attached to the fixed framework. From this contact plate *h* passes a conducting wire *k*¹, which is connected to a battery or dry cell *k* which is also connected to the lamp *l*.

With this arrangement, the pendulum like device will remain suspended vertically in equilibrium while the machine is flying level. When however the machine banks or tilts to one side, the pendulum remains substantially vertical but moves along the slot as the wings come into an inclined position. When the angle for which the device is set is reached, contact is made between the studs or plates or the like *d* and *h* and a circuit is completed through the light, calling the attention of the pilot to the tilt of the machine.

In a preferred arrangement I provide two of the pendulum like devices, one for each side and I provide two lamps of different colours, for instance red for the left wing

and green for the right wing, thus enabling the pilot to tell by the colour of the light not only that the tilt has reached a certain amount but also whether the left or the right wing is uppermost.

Should the pilot not wish to correct the level of the machine, and the wing continues to rise, the contacts *d* and *h* will still touch one another as the pendulum will remain at 10 the end of the slot *m* and the warning light will continue to be exhibited.

It will be understood that the particular method of carrying out the invention may be varied within a fair interpretation of my 15 claims.

What I claim and desire to secure by Letters Patent of the United States of America is:—

1. A pendulum circuit closer for use in 20 connection with an aeroplane, hydroaero-plane or other aerial craft comprising in combination a framework, a pendulum suspended on a pivot located at the top of said frame, a horizontal frame member beneath 25 said pivot, and having a slot, in which said pendulum swings, said slot being arranged to guide the pendulum in its movement and to limit the amplitude of the swing of said pendulum, an insulated contact carried on 30 said pendulum towards its free end and a

second contact secured to a portion of said framework so as to co-act with the contact on said pendulum when same is swung about its pivot to a predetermined extent, for the purposes set forth.

35

2. A pendulum circuit closer for use in connection with an aeroplane, hydroaero-plane or other aerial craft, comprising in combination a pair of frames, located on each side of the plane of symmetry of the machine, a pendulum supported on a pivot located at the top of each of said frames, horizontal frame members in said frames beneath the pivots, each having a slot, in which the pendulum swings, said slots guiding the 40 pendulums in their movement and being of such length as to limit the amplitude of the swing of said pendulums, an insulated contact plate carried on the outer side of each of said pendulums, towards their free ends, 45 and a second contact secured to a portion of each of said frames and adapted to co-act with the contact on the pendulum adjacent thereto, for the purposes set forth.

40

In testimony whereof I affix my signature 50 in presence of two witnesses.

WILLIAM ALEXANDER McDougall.
